ATTORNEY

UNITED STATES PATENT OFFICE.

WILLIAM P. BOYLE, OF SPRINGFIELD, MASSACHUSETTS.

BURNER FOR GAS-FURNACES.

1,328,225.

Specification of Letters Patent. Patented Jan. 13, 1920.

Application filed October 30, 1918. Serial No. 260,372.

To all whom it may concern:

Be it known that I, WILLIAM P. BOYLE, a citizen of the United States of America, and resident of Springfield, in the county 5 of Hampden, and State of Massachusetts, have invented certain new and useful Improvements in Burners for Gas-Furnaces, of which the following is a full, clear, and exact description.

10 This invention relates to improvements in burners for gas furnaces, and particularly to the provision of means for supplying air and gas under pressure to the combustion points or burners without requiring 15 a mixture of the air and gas in advance of combustion, and so as to insure complete combustion of the gas.

Another object of the invention is to provide a gas furnace with gas and air feeding 20 means so arranged that back fire in the fuel conduit is rendered impossible, so that the putting out of adjoining or neighboring burners of the same, or another system, will be rendered impossible, owing to such back 25 fire.

With the above and other objects in view, the invention relates to certain combinations, constructions and arrangements of parts clearly described in the following specification, and illustrated in the accompanying 30 drawings, in which,—

Figure 1 is a vertical sectional view through my improved burner.

Fig. 2 is a plan view thereof.

35 Fig. 3 is a detail end view of the air inlet of the burner.

Fig. 4 is a detail end view of the gas inlet of the burner.

40 Fig. 5 is a detail view, partly in section, on a reduced scale, showing the arrangement of a pair of burners with a gas furnace.

Referring to the accompanying drawings, A designates a suitable gas furnace having 45 an outer wall 5 which is provided with one or more openings 6, the sides of which diverge inwardly.

One or more burners 7 are arranged adjacent to the openings 6 so as to project the 50 combined air and fuel stream through the openings 6, said burners being spaced relative to said openings so that air will be sucked through the openings by the combined air and gas stream.

55 Each burner 7 consists of a T-casting or

body, which provides an internally threaded gas inlet 8, an internally threaded air inlet 9, and an internal partition 10, which divides the interior of the T-shaped casting into a gas chamber 11, and an air chamber 60 12, the gas chamber 11 having normal open communication with the gas inlet 8 and the air chamber 12 having normal open communication with the air inlet 9.

A burner tube 13 is threaded at its lower 65 end in a threaded opening 14, formed in the partition 10, and the opposite end of said burner tube projects through the outlet 15 of the T-shaped body.

The outer end of the burner tube 13 is 70 formed with a converging mouth 16, adapted to cause a concentrated flow of the air through said burner tube.

A gas nozzle collar 17 has a pendant externally threaded flange 18 which is threaded 75 in the outlet 15, and the outer end of said nozzle is provided with a reduced mouth 19, adapted to concentrate the gas stream flowing around the burner tube.

The burner tube is spaced concentrically 80 from the gas nozzle member, and said burner tube is provided with spacing lugs 13^a adapted to maintain said burner tube concentrically spaced from the gas nozzle member.

Air is supplied to the central tube by means of an air pipe 21 which is connected with the inlet 9, and gas is supplied to the annular space around said tube by means of the pipe 20, which is connected with the inlet 8. The pipes 21 and 20 are connected 90 with suitable supply pipes in which a flowing pressure is maintained by means of suitable blowers or other devices.

The air flows through the feed conduit or 95 pipe 21 to the combustion point at the tip of the burner tube 13 without being mixed with gas; and the gas flows through the air conduit or pipe and through the space between the gas nozzle and central tube without being mixed with air, so that it is impossible for the fire to travel backwardly in either pipe since gas alone or air alone will not support combustion.

Since the gas and air discharge into the 105 atmosphere at the same time, they are mixed only at the point of combustion.

The gas is supplied to the air in an annular stream, which surrounds the air stream, whereby the gas is prevented from 110

escaping into the atmosphere without being mixed with air, and, therefore, being properly burned.

It will be seen that the relation of the gas nozzle to the air tube permits of the increase or decrease of the diameter of the gas stream projected around the burner tube, by threading or unthreading the gas nozzle on the body of the burner 7.

10 In order to lock the member 17 in adjusted position against the outlet 15, a suitable locking device, such as a set screw 24 may be arranged along the outlet 15 to bear against the gas nozzle 17.

15 I claim:—

1. A gas burner consisting of a body having separate inlets and a partition dividing the body into independent chambers, a tube connected with the partition and in communication with one of the chambers and one of the inlets, said tube having an externally and internally beveled mouth, a collar threaded on the body around the tube and spaced therefrom and provided with a deflecting mouth disposed adjacent the mouth of the tube, and means for locking the collar in adjusted position.

2. A gas burner for industrial furnaces consisting of a hollow body formed with 30 separate inlets and a single outlet, a partition within said body dividing the body into separate chambers, said partition having an internally threaded opening, a tube threaded in said opening and extending through the

outlet, and a nozzle threaded in the outlet 35 and inclosing the outer end of the tube, the inner wall surface of the nozzle being provided with an inwardly beveled terminal portion and concentrically spaced from the outer wall surface of the tube to provide an 40 annular passage therebetween, the tube being in direct communication with one of the chambers of said body and not in communication with the other of said chambers, and the annular space between the nozzle and 45 the tube being in communication with the other chamber and not with the first chamber.

3. A gas burner for industrial furnaces consisting of a T-shaped body formed with 50 opposing inlets and a single outlet disposed on a line between the inlets, a partition within said body dividing the same into separate chambers and separating the inlets from each other, said partition having 55 an opening therein, a tube connected with said opening to receive a supply of air through the inlet in communication therewith, and a nozzle having a flange threaded into the outlet and surrounding and spaced 60 concentrically from the tube to receive a supply of gas from the other inlet, the outer end of the tube having an inwardly deflected mouth and the outer end of the nozzle having an inwardly deflected portion 65 surrounding the mouth of the tube.

Signed by me at Springfield, Mass.
WILLIAM P. BOYLE.
